UNITED STATES PATENT OFFICE.

FOREST V. DETWILER, OF POTTSTOWN, PENNSYLVANIA.

HYDROCARBON BURNER.

1,422,752.

Specification of Letters Patent. Patented July 11, 1922.

Application filed November 24, 1919. Serial No. 340,105.

To all whom it may concern:

Be it known that I, FOREST V. DETWILER, a citizen of the United States, residing at Pottstown, in the county of Montgomery and State of Pennsylvania, have invented 5 certain new and useful Improvements in Hydrocarbon Burners, of which the following is a specification.

This invention relates to improvements in 10 hydrocarbon burners for boilers, furnaces, and the like, and one of the objects of the invention is to improve and simplify the construction thereof and reduce the cost of manufacture.

15 A further object is to provide an improved burner of this character which will be of a sectional construction and having improved means for securing the sections together.

20 A further object is to provide an improved means for supporting the burner whereby it may be arranged at any desired elevation in the fire pot of a boiler or furnace.

25 To the attainment of these ends and the accomplishment of other new and useful objects as will appear, the invention consists in the features of novelty in substantially the construction, combination and arrangement of the several parts, hereinafter more fully described and claimed and shown 30 in the accompanying drawings illustrating this invention and in which;

Figure 1 is a side elevation of an improved burner of this character constructed 35 in accordance with the principles of this invention.

Figure 2 is a left hand end elevation of Figure 1.

40 Figure 3 is a detail sectional view of a valve casing and valves for controlling the burner.

Figure 4 is a detail sectional view on line 4—4, Figure 3.

45 Figure 5 is a vertical sectional view taken on line 5—5, Figure 2.

Figure 6 is a top plan view of Figure 5.

Figure 7 is a detail sectional view on line 7—7, Figure 5.

50 Figure 8 is an irregular sectional view taken on line 8—8, Figure 5.

Figure 9 is an enlarged detail sectional view showing one manner of packing between the joints.

Referring more particularly to the drawings the burner body is of sectional construction comprising a bottom portion 10 and upper portion 11. The bottom portion 10 is of a sectional construction and is secured together in any suitable manner preferably by means of flanges 12 on the inside of the section and fastening bolts 13 passing through the flanges. The bottom is of a frusto-conical configuration and is provided with a laterally projecting portion 14 terminating preferably in a priming pan 15 formed integral therewith.

The upper portion 11 is also of a sectional construction and is of a frusto-conical configuration of a size to encompass and be spaced from the portion 10. The wall of the portion 11 is provided with burner slots 16 preferably arranged vertically therein and the upper portion is adapted to rest upon the laterally projecting portion 14 of the bottom, and may, if desired, be rotated about the bottom portion. The sections of the top portion 11 are held together by means of suitable flanges 17 and arranged on the abutting edges, and through which flanges suitable fastening bolts 18 pass.

The top 19 of the bottom portion 10 is provided with an opening 20 therethrough and around the opening is provided a seat 21 in which a flange 22 of a collar 23 is adapted to be seated, and this collar 23 is adapted to be held in position by means of suitable fastening bolts 24. The collar is provided with internal screw threads and engaging the threads is a threaded end of an inlet pipe 25 which discharges into the chamber formed by the portions 10 and 11 of the burner to convey the vapor into the burner and which vapor passes through the burner openings or slots 16 to be ignited. The other end of the pipe 25 is open as at 26 and the parts thus formed may be supported by a base 27 to which the pipe 25 may be secured in any suitable manner such as by means of a fastening bolt 28 passing through a flange 29 on the pipe.

Encompassing the burner body thus formed is a vaporizing pipe 30 which may be supported in any suitable manner such as by means of brackets 31. To the outlet end 32 of the vaporizing pipe 31 is connected a nozzle 33 which discharges into the opening 26 of the pipe 25 and the nozzle is provided

with a valve 34 for controlling the same. An indicator 35 may also be provided for the valve. The nozzle 33 may be supported in any suitable manner, preferably by resting upon a portion 36 of the base 27 and may be secured in position by a suitable fastening device 37. A drip pan 38 may be provided in the base under the nozzle.

The inlet end 39 of the pipe 30 is connected with a valve casing 40 and this valve casing is provided with an inlet passage 41 to which is connected a supply pipe 42 which receives its supply from a supply tank 43. Pressure is exerted in the tank 43 in any suitable manner such as by means of a pump 44 and the fuel is supplied from the tank 43 through the pipe 42 into the valve casing 40 and is controlled by a valve 45 having an indicator 46.

20 The valve casing 40 is provided with a passage 47, one end of which has communication with the inlet end 39 of the pipe 40 and is controlled by a valve 48 provided with an indicator 49.

25 The other end of the passage 47 is connected with a priming pipe 50 and is controlled by a valve 51 having an indicator 52. The priming pipe 50 is seated in the priming pan 15 and extends around the base of 30 the burner beneath the vaporizing pipe 30. The priming pipe is provided with openings 53 in its bottom to deliver fuel to the priming pan. The specific construction of this valve mechanism, although herein fully 35 described, will constitute the subject matter of a separate application.

To start the burner all that is necessary assuming that sufficient pressure is in the tank 43 is to open the valve 45 to permit 40 the fuel to flow into the opening 41 and into the passage 47. The valve 51 is then opened to supply the priming pan with fuel. When sufficient fuel is supplied it is ignited and the valve 51 is closed. The ignition of 45 the fuel in the priming pan 15 heats the generating pipe 30 and when the pipe 30 is sufficiently hot the valve 48 is opened to permit the fuel to flow into the pipe 30 where it will be vaporized and will be delivered from the pipe 30 through the nozzle 33 into the pipe 25 and into the burner bottom where it will be ignited at the openings 16.

50 In order to provide a means whereby the elevation of the burner may be varied in the fire pot a suitable adjustable support may be provided and embodies an upright 54 which is provided with threaded extremities. One extremity has engagement with 55 a collar 55 that is seated in a sectional base 56 upon which the body of the burner rests, the sections of the base 56 being secured together by suitable fastening devices 57.

55 The other end of the upright has threaded engagement with a collar 57 seated in a

supplemental base or support 58, and which supplemental base or support is also of a sectional construction, the sections being held together by means of suitable fastening devices 59.

70 The walls of the portions 10 and 11 at their abutting edges may be provided with any suitable packing 60 and to that end the abutting edges may be provided with recesses 61 to receive the packing.

75 A flame deflector may be provided for directing the flame away from the burner and for separating the same. This deflector may be of any desired size and configuration but embodies sections 62 having a deflecting surface 63 and the sections are secured together by means of abutting ears 64 through which a fastening device 65 passes.

80 The deflector thus formed is provided with an opening 66 through its body and the deflector is adapted to engage and rest upon the top of the outer section 11 of the burner, so that the flanges 17 of the sections will stand within the opening 66. When 85 the deflector is in position it will be manifest that the clamping of the ears 64 together will serve as a means for causing the sections of the deflector to grip the top of the section 11, though when it is desired the 90 deflector may be readily removed.

95 If desired, and in order to provide an additional securing means for the pipe 25 (see Figure 8) there may be provided spaced ears 67 on the base 27 adjacent the point 100 where the entrance opening 26 of the pipe 25 is located and fastening screws 68 may be provided to pass through these ears to engage the outer surface of the end of the pipe 25.

105 While the preferred form of the invention has been herein shown and described, it is to be understood that various changes may be made in the details of construction and in the combination and arrangement of the 110 several parts within the scope of the claims without departing from the spirit of this invention.

110 What is claimed as new is:—

115 1. A hydrocarbon burner embodying a burner chamber of a substantially frustoconical configuration and embodying top and bottom portions separate from each other and each being of sectional construction, means for securing the respective sections together, the top portion having burner slots, a vapor inlet pipe connected with the bottom portion and discharging into the burner, a vaporizing pipe encompassing the burner, and a nozzle connected 120 with the vaporizing pipe and discharging 125 into the said inlet pipe.

130 2. A hydrocarbon burner embodying a burner chamber of a substantially frustoconical configuration and embodying top

- and bottom portions separate from each other and each being of sectional construction, means for securing the respective sections together, the top portion having burner slots, a vapor inlet pipe connected with the bottom portion and discharging into the burner, a vaporizing pipe encompassing the burner, a nozzle connected with the vaporizing pipe and discharging into the said inlet pipe, a priming pan arranged on the outside of the burner and beneath the said vaporizing pipe, and means for supplying fuel to the priming pan.
3. A hydrocarbon burner embodying a burner chamber of a substantially frustconical configuration and embodying top and bottom portions separate from each other and each being of sectional construction, means for securing the respective sections together, the top portion having burner slots, a vapor inlet pipe connected with the bottom portion and discharging into the burner, a vaporizing pipe encompassing the burner, a nozzle connected with the vaporizing pipe and discharging into the said inlet pipe, a supporting base for the burner, a supplemental supporting base, and an adjustable standard interposed between the said bases whereby the elevation of the burner may be varied.
4. A hydrocarbon burner embodying a burner chamber of a substantially frustconical configuration and embodying top and bottom portions separate from each other and each being of sectional construction, means for securing the respective sections together, the top portion having burner slots, a vapor inlet pipe connected with the bottom portion and discharging into the burner, a vaporizing pipe encompassing the burner, a nozzle connected with the vaporizing pipe and discharging into the said inlet pipe, a supporting base for the burner, a supplemental supporting base, a standard adjustably connected with the bases, said bases each being of sectional construction, and means for securing the sections together.
5. A hydro-carbon burner embodying a burner chamber, said chamber embodying a top and a bottom portion spaced and separate from each other, the top portion having burner slots, the lower portion being of sectional construction, portions of the wall of the bottom sections being shaped to form a seat opening therethrough, a non-sectional collar arranged in said opening, means securing the collar to each section, a vapor inlet pipe having threaded engagement with the collar and discharging into the burner, a vaporizing pipe encompassing the burner, a nozzle connected with the vaporizing pipe and discharging into the said inlet pipe, and means for securing the top sections together.
6. A hydro-carbon burner embodying a burner chamber, said chamber embodying a top and a bottom portion spaced and separate from each other, the top portion being of sectional construction and having burner slots, the lower portion being of sectional construction, portions of the wall of the bottom sections being shaped to form a seat opening therethrough, a non-sectional collar arranged in said opening, means securing the collar to each section, a vapor inlet pipe having threaded engagement with the collar and discharging into the burner, a vaporizing pipe encompassing the burner, a nozzle connected with the vaporizing pipe and discharging into the said inlet pipe, means for securing the top sections together, the last recited means embodying abutting flanges, and fastening bolts passing through the said flanges.
7. A hydrocarbon burner embodying a burner chamber, said chamber embodying a top and a bottom portion spaced and separate from each other, the top portion being of sectional construction and having burner slots, the lower portion being of sectional construction, portions of the wall of the bottom section being shaped to form a seat opening therethrough, a non-sectional collar arranged in said opening, means securing the collar to each section, a vapor inlet pipe having threaded engagement with the collar and discharging into the burner, a vaporizing pipe encompassing the burner, a nozzle connected with the vaporizing pipe and discharging into the said inlet pipe, means for securing the top sections together, additional means for securing the bottom sections together, said additional means embodying abutting flanges on the bottom sections, and fastening bolts passing through the last recited flanges.
8. A hydrocarbon burner embodying a burner chamber, having burner slots, a vaporizing pipe encompassing the burner, means whereby the vapor from the said pipe will be delivered into the said chamber, and a sectional annular flame deflector detachably secured to the top of the chamber and projecting beyond the wall thereof.
9. A hydrocarbon burner embodying a burner chamber, said chamber embodying a top and a bottom portion separate from each other, said portions being spaced and one encompassing the other; each of said portions being of sectional construction, means for securing the respective sections together, there being burner openings in the outermost member, a vaporizing pipe encompassing said chamber, and means whereby vapor from said pipe may be discharged into the said chamber.
10. A hydrocarbon burner embodying a burner chamber, said chamber embodying top and bottom portions separate from each

other, one of said portions encompassing the other portion and being spaced therefrom, each of said portions being of sectional construction, abutting flanges on the proximate 5 edges of the respective sections, fastening devices passing through the flanges, there being burner openings through the outermost portion, a vaporizing pipe encompassing the chamber, and means whereby vapor 10 from the pipe may be delivered into the said chamber.

11. A hydrocarbon burner embodying a burner chamber, said chamber embodying top and bottom portions separate from each 15 other, one of said portions encompassing the other portion and being spaced therefrom, each of said portions being of sectional construction, abutting flanges on the proximate edges of the respective sections, fastening 20 devices passing through the flanges, there being burner openings through the outermost portion, a vaporizing pipe encompassing the chamber, means whereby vapor from the pipe may be delivered into the said 25 chamber, and a flame deflector removably

seated upon the top of the said chamber and projecting beyond the outer wall thereof.

12. A hydrocarbon burner embodying a burner chamber, said chamber embodying top and bottom portions separate from each 30 other, one of said portions encompassing the other portion and being spaced therefrom, each of said portions being of sectional construction, abutting flanges on the proximate edges of the respective sections, fastening 35 devices passing through the flanges, there being burner openings through the outermost portion, a vaporizing pipe encompassing the chamber, means whereby vapor from the pipe may be delivered into the said 40 chamber, a sectional flame deflector removably seated upon and encompassing the top of the said chamber and projecting beyond the wall thereof, and means for clamping the deflector to the top of the chamber. 45

In testimony whereof I have signed my name to this specification, on this 8th day of November, A. D. 1919.

FOREST V. DETWILER.
